[57] CLAIM

The ornamental design for an animal ice pack, as shown and described.

DESCRIPTION

FIG. 1 is a front and left side perspective view of an animal ice pack showing my new design;

FIG. 2 is a rear and left side perspective view thereof, showing my new design, with the right side constituting a mirror-image of the left side;

FIG. 3 is a rear perspective view thereof, in use condition; and,

FIG. 4 is a rear right side perspective view thereof, in use condition.

The broken line illustration showing a deer carcass in FIGS. 3 and 4 is for illustrative purposes only and forms no part of the claimed design.
